UNITED STATES PATENT OFFICE

115,463

DESIGN FOR A CABINET FOR CIRCULATING HEATER

Georges Wilmet, Roslyn, N. Y., assignor to Motor
Wheel Corporation, Lansing, Mich., a corpora-
tion of Michigan

Application March 31, 1939, Serial No. 83,942

Term of patent 14 years

To all whom it may concern:

Be it known that I, Georges Wilmet, a citizen
of Belgium, residing at Roslyn, in the county of
Nassau and State of New York, have invented
a new, original, and ornamental Design for a
Cabinet for Circulating Heater, of which the fol-
lowing is a specification, reference being had to
the accompanying drawing, forming a part there-
of.

In the drawing, the single figure is a perspec-
tive view of a cabinet for circulating heater em-
bodying my new design. Both sides of the cabi-
net are alike. The back is plain.

I claim:

The ornamental design for a cabinet for circu-
lating heater, as shown and described.

GEORGES WILMET.
